UNITED STATES PATENT OFFICE.

HARRIET A. BROWN, OF BOSTON, MASSACHUSETTS.

DRESS-WAIST.

SPECIFICATION forming part of Letters Patent No. 392,493, dated November 6, 1888.

Application filed November 18, 1887. Serial No. 255,556. (No model.)

To all whom it may concern:

Be it known that I, HARRIET A. BROWN, a citizen of the United States, residing at Boston, in the county of Suffolk and State of Massachusetts, have invented certain new and useful Improvements in Dress - Waists, of which the following is a specification, reference being had to the accompanying drawings.

The object of my invention is an improvement in the fit and appearance of dress-waists; and it consists in the form, adaptation, and combination of parts or pieces of a dress-waist, as hereinafter set forth, and specifically pointed out in the claim.

15 In the drawings, Figures 1 and 2 are two views of a dress-waist embodying my invention. Fig. 3 shows the piece to form the front and back of one-half of the waist. Fig. 4 shows the piece to form a side piece of the back. 20 Fig. 5 shows one and Fig. 6 the other piece for a side of the waist.

Each half of the common dress-waist, which is designed to conform closely to the figure of the person, is composed of these pieces—25 namely, a front, A, back B, side piece of the back, C, and one piece at the side in place of the two side pieces, D and E, the front piece being bifurcated at its lower part.

The front and back has heretofore been of 30 two pieces joined together by means of a seam on the shoulder, the position of which seam being indicated by the dotted line a. I make the front and back of one piece, as shown. Not only is the labor of making the seam on 35 the shoulder thus dispensed with, but the waist presents a much better appearance without such seam. The improved effect is particularly noticeable and pleasing when striped material is employed, since the stripes may 40 extend over the shoulder without a break.

It is common to cut the front so that it is bifurcated at the lower part; but the two extensions have heretofore been broad at the lower edge of the waist and the fit not as perfect as desired. I cut the front so that a much 45 better effect is attained. It is not necessary

to specify herein the particular curves or degree of curvature of these extensions b and c as cut by me, since I am able to gain the desired result mainly from the fact that I bring 50 the part c at the front of the waist to a point at its lower end in such a manner that the part c is tapering substantially through its entire length, making what I term a "needle-point." By having the part c thus pointed 55 the waist may be caused to conform to the curvature of the form at this part more perfectly and readily than it has been possible heretofore. I use two pieces, D and E, at the side of the waist instead of one, as heretofore. 60 I have found that it is quite difficult, if not impossible, to cause a dress-waist to conform at the sides to a very short-waisted or corpulent person by the employment of only one piece at the side. Though each of the side 65 pieces which I use does not differ materially in general shape from the one piece in common use, yet the outlines may be so changed as to degree of curvature, &c., according to the measurements for a person, by the employment of two pieces that the general and specific form of the two when combined is quite different from that of the one alone, and the effect is much more pleasing and satisfactory.

Either of the several parts of my invention 70 may be employed without the others, the other parts of the dress-waist being of the ordinary make.

Therefore I claim as my invention—

A dress-waist each half of which is formed 80 of a front and back of one piece, a side piece at the back, and two side pieces between said side piece of the back and the front, the front being bifurcated and having the extension at the front pointed and tapering substantially 85 through its entire length, substantially as specified.

HARRIET A. BROWN.
